UNITED STATES PATENT OFFICE.

IGNATIUS BOND, OF EVANSTON, ILLINOIS.

WALL-PLATE FOR ELECTRIC FIXTURES.

No. 914,107.

Specification of Letters Patent. Patented March 2, 1909.

Application filed March 9, 1908. Serial No. 419,974.

To all whom it may concern:

Be it known that I, IGNATIUS BOND, a citizen of the United States, and a resident of Evanston, county of Cook, and State of Illinois, have invented certain new and useful Improvements in Wall-Plates for Electric Fixtures, of which the following is a clear, full, and exact description.

My invention relates to wall plates for electric fixtures, and particularly lamp-sockets, switches and the like, and its object is to provide a wall-plate that is especially adapted for use in conjunction with electric wire molding or even exposed insulated wire to give the same a more finished and complete appearance than can be obtained without them. This I accomplish by the means hereinafter fully described, and as particularly pointed out in the claims.

20 In the drawings:—Figure 1 is a perspective view of my invention showing one form of my improvement. Fig. 2 is a plan view of my invention with the electric fixture removed. Fig. 3 is a longitudinal section taken on dotted line 3, 3, Fig. 2. Fig. 4 is a transverse section taken on dotted line 4, 4, Fig. 2. Fig. 5 is a plan view of a modified form of my invention. Fig. 6 is a similar view of yet another modification. Fig. 7 is 30 a similar view of another modification. Fig. 8 is a top edge view of the form shown in Fig. 7. Fig. 9 is a plan view of still another modification of my invention with the fixture removed and Fig. 10 is an edge view of 35 the same with the molding and wall in section.

Referring to the drawings, A represents a vertically disposed strip of electric wire molding, having its lower end inserted in the 40 socket b of my improved wall-plate B, which latter has a square base and has a central opening c of sufficient diameter to receive the porcelain supporting-base of a switch C, or other electric fixture, for the circuit established by the wires confined within the molding. The central part of my improved wall-plate, in which said opening c is made, is raised so as to stand out from its basal edges a distance slightly greater than the 45 thickness of the molding. The web of metal forming the margins of opening c slope back

from the edges of its central opening preferably, in concave lines, and gracefully merge into the square described by the outer edges of the same. The side-walls of the socket are in the same plane as the sides of the mold, and strike into the sloping surface of the raised central portion of plate B and greatly contribute to making a socket that produces a pleasing termination for the end 60 of the molding inserted therein.

In order to provide means for securing these wall-plates to the wall, I have provided one or more lugs e, e, which project towards the axis of opening c, from the inner 65 surface of the sloping portion thereof, and which are provided with screw-holes through which the screws are inserted that are driven into the wall. In order to secure the fixture to the wall-plate I have provided the same 70 with a suitable transaxial cross-bar E, which bridges the space between the sloping sides of the wall-plate back of opening c and slightly in advance of lugs e, e. The fixtures are generally secured in place by screws 75 tapped through their porcelain bases and these screws are tapped into bar E, but if screws are not employed for this purpose the said bar furnishes a means for securing other fastening devices to said wall-plate. 80

In Fig. 6 of the drawings I show a modified construction of my invention which shows a wall-plate G having two openings g, g for switches (not shown) in its flat raised surface and a vertical socket h for each opening into which the adjacent end of the wire molding is inserted. This modification may be provided with lugs f, f, and cross-bars F, F, back of each opening, but either the lugs of the cross-bar, or both, may be omitted. 90

In Fig. 5 I show another modification in which the wall-plate is made round and the socket for the molding is omitted, and also the cross-bar back of the opening, which appears in the other designs shown. 95

In Figs. 7 and 8 another design is shown, which corresponds in construction to that shown in the first four figures of the drawings with the exception that the plate H has two corresponding parallel sockets j, j, each of which, instead of being rectangular in cross-section, have their outer surfaces 100

rounded, and are each only large enough to permit the passage of the tubular insulation *k* of one wire *K*. The modification just referred to also dispenses with lugs *e*.

5 In Figs. 9 and 10 I show yet another modification which is similar to the wall-plate shown in Fig. 1 of the drawings, excepting that in addition to the socket there shown it is provided with a similar socket I extending 10 in alinement therewith diametrically opposite. This modification is designed for use principally on the ceiling where the molding leads to and from the wall-plate. This modification is provided with lugs *J*, *J*, which 15 are similar to lugs *e*, *e*, but dispenses with the cross-bar.

What I claim as new is:

1. A wall-plate for electric fixtures consisting of a plate of suitable material the 20 central portion of which is raised and has an opening therein, lugs projecting inwards back of the plane of said opening that have screw-holes therein and a cross-bar located between said lugs and opening and bridging 25 the space back of the plane of said opening.

2. A wall-plate for electric fixtures consisting of a plate of suitable material the central portion of which is entirely cut away and has a raised portion surrounding said 30 cut away portion, and is provided with an integral covered socket which extends from its outer edge into the space back of the plane of said opening and the upper portion of said socket being in the same plane as the top of said central raised portion.

3. A wall-plate for electric fixtures consisting of a plate of suitable material the central portion of which is raised and has an opening therein, and is provided with 40 integral embossed means that extend from the edge of said plate into the space back of said opening whereby access is had to the raised portion from the edge of said plate, said means being covered and the top thereof 45 being in the same plane as the top of said central raised portion.

4. A wall-plate for electric fixtures consisting of a plate of suitable material the central portion of which is entirely cut away 50 and has a raised portion surrounding said cut away portion, floating lugs projecting inwards back of the plane of the outer edge of said raised portion that have screw-holes therein, and said wall-plate having an integral covered socket extending from its outer edge into the space back of the plane of said opening and the upper portion of said socket being in the same plane as the top of said central raised portion.

60 5. A wall-plate for electric fixtures consisting of a plate of suitable material the central portion of which is raised and has an opening therein, floating lugs projecting inwards back of the plane of the outer edge

of said raised portion that have screw-holes 65 therein and said wall-plate being provided with integral embossed means that extend from the edge of said plate into the space back of said opening whereby access is had to the raised portion from the edge of said 70 plate, said means being covered and the top thereof being in the same plane as the top of said raised portion.

6. A wall-plate for electric fixtures consisting of a plate of suitable material the 75 central portion of which is entirely cut away and has a raised portion surrounding said cut away portion, a cross bar extending entirely across the space back of the plane of the outer edge of said raised portion, and said wall-plate having an integral covered 80 socket extending from the outer edge of the plate into the space back of the plane of said opening and the upper portion of said socket being the same plane as the top of said central raised portion.

7. A wall-plate for electric fixtures consisting of a plate of suitable material the central portion of which is raised and has an opening therein, a cross-bar extending 90 entirely across the space back of the plane of the outer edge of said raised portion, and said wall-plate being provided with integral embossed means that extend from the edge of the plate into the space back of said opening whereby access is had to the raised portion from the edge of said plate, said means being covered and the top thereof being in 95 the same plane as the top of said central raised portion.

8. A wall-plate for electric fixtures consisting of a plate of suitable material the central portion of which is raised and has an opening therein, lugs projecting inwards back of the plane of said opening that have 105 screw-holes therein, a cross-bar located between said lugs and opening and bridging the space back of the latter, and said wall-plate having a socket extending from the outer edge of the plate into the space back 110 of the plane of said opening.

9. A wall-plate for electric fixtures consisting of a plate of suitable material the central portion of which is raised and has an opening therein, lugs projecting inwards back of the plane of said opening that have 115 screw-holes therein, and a cross-bar located between said lugs and opening and bridging the space back of the latter, said wall-plate being provided with means that extend from the outer edge of the plate into the space back 120 of said opening whereby access is had to said raised portion from the edge of said plate.

10. A wall-plate for electric fixtures consisting of a plate of suitable material the central portion of which is raised and has an opening therein, diametrically opposite lugs

projecting inwards back of the plane of said opening that have screw-holes therein and a transaxial cross-bar located between said lugs and opening and bridging the space back of the latter, said lugs and said cross-bar extending in planes at an angle to each other.

In testimony whereof I have hereunto set my hand and seal this 6th day of March, A. D., 1908.
